UNITED STATES PATENT OFFICE.

RUSSELL W. GUILFORD, OF AUBURN, INDIANA, ASSIGNOR TO WILLIAM H. MCINTYRE, OF AUBURN, INDIANA.

FLY-WHEEL.

No. 911,540.

Specification of Letters Patent.

Patented Feb. 2, 1909.

Application filed January 27, 1908. Serial No. 412,748.

To all whom it may concern:

Be it known that I, RUSSELL W. GUILFORD, a citizen of the United States, residing at Auburn, in the county of Dekalb, in the 5 State of Indiana, have invented certain new and useful Improvements in Fly-Wheels; and I do hereby declare that the following is a full, clear, and exact description of the invention, which will enable others skilled in 10 the art to which it appertains to make and use the same, reference being had to the accompanying drawings, which form part of this specification.

My invention relates to improvements in 15 fly-wheels.

It is well known that in automobiles and other motor-vehicles automatically operated cooling fans for the engine cylinders are employed, and are so arranged as to direct a 20 cooling blast of air upon the engine; and that this cooling blast is usually directed upon the central portion of the engine from which it is irregularly deflected with more or less uncertain efficiency to the heated cylinders.

The object of my present invention is to provide a fly-wheel of novel construction whose spokes and perimeter are so arranged as to perform the additional function of 30 cooling fans, and to direct the cooling blast in two directions to the opposite cylinders of the engine by diverting the blast at acute angles to the axis of the wheel instead of in a direct line with the axis.

The principal novel feature of my invention resides in the construction and relative arrangement of the wheel spokes to divert the cooling blast from a right line with the axis to lines inclined to such axis, for 40 the purpose of directing such blast directly upon opposite and separated engine cylinders.

Similar reference numerals indicate like parts in the several views in which—

Figure 1 is a perspective view of the fly-wheel showing the construction of the spokes and the beveled side of the perimeter. Fig. 2 is a horizontal central section of the fly-wheel showing more clearly the beveled 50 perimeter and the flanged spokes, the fly-wheel being in position on the crank-shaft, and also showing a plan view of the crank case and the engine cylinders, the latter being partly broken away. Fig. 3 is a plan 55 view of the fly-wheel with its perimeter

partly broken away to show more clearly the relation of the inclined spokes to the lateral flanges thereof.

My improved fly-wheel of any proper dimensions and material has a suitable perimeter 1, a suitable concentric hub 2, having a proper central opening 6 and a series of radial spokes 3 preferably integral with both the rim and the hub.

The spokes preferably have at their outer 65 ends a width equal to that of the rim 1, and at their inner ends a width equal to that of the hub.

The width of the wheel rim 1 is preferably somewhat greater than the length of 70 the hub, as shown in Figs. 2 and 3.

The wheel rim has one edge thereof inwardly beveled as shown at 4, for the purpose hereafter described.

The spokes are inclined to corresponding radial planes arranged at right angles with the axis of the hub as shown in Fig. 3, and each is provided upon one edge thereof with a lateral flange 5, arranged at an angle thereto and in the plane of the axis of the 80 hub. The outer end of this flange projects laterally a proper distance beyond the beveled edge 4, is preferably rounded, as shown, and the flange then gradually tapers to the adjacent face of the hub.

The angle of inclination and the width of the spokes, as well as the contour and amount of lateral extension of the flanges 5, and the inclination of the beveled portion 4 of the rim, are all immaterial so long as they perform efficiently their intended function about to be described.

In Fig. 2 the relative arrangement of the fly-wheel and the cylinders 7 to be cooled is shown. These cylinders preferably have the 95 usual cooling fins 8, and are fixed upon opposite sides of the crank case 9.

The operation and manner of employing my invention thus described is obvious and briefly stated is as follows: The fly-wheel 100 is fixed upon one end of the crank-shaft 10 in proper proximity to the engine cylinders to be cooled, with the face of the fly-wheel having the flanges 5 thereon adjacent to and in parallel relation with the surfaces to be 105 cooled. The wheel is then rotated or driven to the right in Fig. 1 whereby the inclination of the spokes produces a suction, and both the bevel face 4 of the rim, and the lateral flanges 5 serve the function of directing the 110

air blast produced by the revolution of the wheel in two directions and at acute angles to the plane of the wheel or upon the separated and aligned cylinders to be cooled, as indicated by arrows in Fig. 2, instead of directing the air in one direction and at right-angles to the plane of the wheel as is done in the usual construction of cooling fans.

10 My improved fly-wheel is thus of simple and economical construction and not only is adapted for the additional air cooling function, but is adapted to perform that function by driving the air blast and directing it in 15 two opposite directions, and at an acute angle to the face of the wheel.

Having thus described my invention and the manner of employing the same what I desire to secure by Letters Patent is:

20 1. A fly-wheel having a perimeter and concentric hub rigidly united by radial spokes whose sides are laterally inclined to the

plane of the wheel, one edge of the said spokes being provided with a lateral flange or projection in right angular relation to 25 the plane of the wheel, as and for the purpose described.

2. A combined fly-wheel and cooling fan, consisting of a wheel-rim and concentric hub rigidly connected by a series of radial 30 spokes, whose sides are inclined to the plane of the wheel the said rim having one edge inwardly beveled, and the said spokes having lateral longitudinal flanges projecting beyond the said beveled edge of the rim and 35 being laterally aligned with the axis of the wheel.

Signed by me at Auburn, Dekalb county, State of Indiana, this 22nd day of January, A. D. 1908.

RUSSELL W. GUILFORD.
